UNITED STATES PATENT OFFICE.

EDWARD A. STALKER, OF ANN ARBOR, MICHIGAN.

AIRPLANE MOTOR.

Application filed May 23, 1925. Serial No. 32,514.

The primary object of my invention is to provide a motor of simple construction that can be cheaply manufactured and efficiently used in an aircraft.

It is a further object of my invention to provide a motor wherein the combustible charges are forced in the combustion chamber by the aid of air from one or more air nozzles placed in the slip stream of the propeller on the cylinder.

It is another object of my invention to provide a two cycle motor for aircrafts wherein the forcing out of exhaust gases from the cylinder chamber will be aided by the air from the propeller slip stream that enters one or more nozzles placed on the cylinder.

My motor is so designed that the axis of the above mentioned nozzle, or nozzles, are placed at an angle between plus or minus thirty degrees from the line of flight.

It is a further object of my invention to provide a converging nozzle in the cylinder that is disposed in the slip stream of the propeller so that the air therefrom will aid in both forcing the combustible mixture into the combustion chamber and after the ignition of the same will force out the exhaust gases through the exhaust port.

With the above and other objects in view, my invention consists in the arrangement, combination and construction of the various parts of my improved motor as described in the specification, claimed in my claims and shown in the accompanying drawings, in which:

Fig. 1 is a horizontal, central sectional view of a part of my improved motor.

Fig. 2 is a vertical sectional view taken on line 2—2 of Fig. 1.

Fig. 3 is a front view, partly in section, of a part of my improved motor.

Fig. 4 is a horizontal sectional view of the piston used in my improved motor showing the passages therein.

Fig. 5 is a longitudinal sectional view of the piston used in my improved device.

I have shown a crank case or engine housing 10 having the cylinders 11 and 12 extending horizontally therefrom. Positioned in the engine housing is the crank shaft 14 to the cranks of which are fitted the connecting rods 15. A propeller 16 is secured to one end of the crank shaft 14. Attached to the ends of the rods 15 and adapted for reciprocation in the cylinders 11 and 12 are

the specially constructed pistons 17 that have the conventional rings 18 bearing against the inner walls of the cylinder.

Disposed on the cylinder 11 in the slip stream of the propeller is the converging nozzle 19 that has the opening 20 into the cylinder chamber 44. This nozzle 19 is preferably placed at an angle of between plus or minus thirty degrees from the line of flight, and immediately adjacent the chamber 44 is tilted upwardly.

An exhaust port 21 is placed at any part of the cylinder circumference just above the top of the piston 17 when the same has completed its down stroke. A section of the head of the cylinder protrudes outwardly as at 22, and into this portion is fitted the spark plug 23. Around the extreme end of the cylinder are also placed the fins 24 that aid in keeping the head thereof cool.

The piston 17 has the passage 25 with the top opening 26 and the side openings 27 and 28 in its head. A pocket 29 that leads into the passage 25 and has the outer opening 30 is also located in the head of the piston 17.

Fuel is carried by the lines 31 through the needle valves 32 and 33 into the air passages 34 and 35 where the same is mixed with air and then forced through the openings 36 and 37 in the cylinder wall into the opening 27 of the pocket 25 and the opening 30 of the passage 29. Thus, the passage of fuel is stopped at all times excepting when the piston 17 has moved to the downward end of its stroke to align the opening 27 and 30 with the openings 37 and 36 in the cylinder wall.

The air passages 34 and 35 which have the butterfly valves 38 and 39 therein terminate in the single passage 40, which is curved as at 41 to prevent the outward circulation of the fuel. The converging nozzle 42 that is placed in the slip stream of the propeller 16 is attached to the end of the passage 40. This nozzle 42 may also be fed by an air line 43 from a source of air under pressure—preferably from the crank case compression.

In the practical use of my improved motor, fuel passes from the lines 31 through the needle valves 32 and 33 into the air passages 35 and 34. At this point air from the nozzle 42 is mixed with the fuel and is forced into the passage 25 and the pocket 29 when the openings 27 and 30 in the piston 17 are aligned with the openings 37 and 36 in the cylinder at the end of the down-

ward stroke of the piston. On the up stroke of the piston, the opening 28 aligns with the opening 20 so that the air from the nozzle 19 blows the combustible mixture from the piston head into the cylinder chamber 44. The charge is then compressed and ignited in the usual manner by the spark plug 23.

When the motor is to run at slow speed, the valves 38 and 39 are so arranged that valve 38 will be open and valve 39 will be closed, thereby forcing a rich mixture into the pocket 29 and a very lean mixture into the passage 27. The pocket 29 is so located that it comes under the spark plug 23 on the top of the piston stroke; thus the rich mixture will be easily ignited and the heat therefrom will burn the leaner fuel.

The exhaust gases are blown out the exhaust port 21, through the cylinder opening 90, (which is uncovered on the inward stroke of the piston 17) by the air that enters the cylinder from the opening 20 that is also opened shortly after the port 21 is opened. The air will be deflected upwardly by the curvature of the opening 20 into the cylinder so as to completely evacuate the cylinder. The same action will occur on the out stroke of the piston, the passage 25 being so constructed and timed that the fuel will not pass from the opening 26 until the opening 20 and port 90 have been closed. The air entering the cylinder chamber 44 from the nozzle 19 also aids in cooling.

I have described my improved motor as having two simple converging air nozzles. I desire it to be understood that a multiple of nozzles may be used, or they (the nozzles) may be compound.

It will be noted that in my detailed description, I have described cylinder 11 with its fittings, but I desire it to be understood that cylinders 11 and 12 and the fittings therefor are exactly alike in every detail.

It is obvious that various changes may be made in the arrangement, combination and construction of the various parts of my improved motor without departing from the spirit of my invention, and it is my intention to cover by my claims such changes as may be reasonably included within the scope thereof.

What I claim is:

1. In combination, a cylinder having a combustion chamber, a piston adapted for reciprocation therein, two air passages leading into said cylinder, means for supplying air to said passages, a fuel source, feed lines leading from said fuel source to said air passages, means in said piston whereby fuel is forced into said combustion chamber from said air passages when the piston reaches a predetermined position of its stroke, means for igniting said fuel and means for

forcing the exhaust gases from said chamber.

2. In combination, a cylinder having a combustion chamber, a piston adapted for reciprocation therein, two air passages having one of their ends leading into the cylinder and the other ends terminating into a single curved passage, a converging nozzle secured on the end of said passage, means for supplying air into said passage through said nozzle, a fuel source, feed lines leading from said source to said two air passages, means in said piston through which fuel is forced by air into said combustion chamber from said air passages when the piston reaches a predetermined position of its stroke, means for igniting said fuel and means for forcing out the exhaust gases from said chamber.

3. In combination, a cylinder having a combustion chamber, a piston adapted for reciprocation therein, a fuel source, means for forcing fuel from said source through the head of said piston into the combustion chamber when said piston reaches a predetermined position of its stroke, means for igniting said fuel, an exhaust port in said cylinder, and a converging nozzle having its opening into said chamber whereby air may be supplied when the piston is at a predetermined position for forcing out the exhaust gases through said exhaust port.

4. In combination, a cylinder having a combustion chamber, a piston adapted for reciprocation therein, two air passages having one of their ends leading into the cylinder and the other ends terminating into a single curved passage, a converging nozzle secured on the end of said curved passage, means for supplying air into said passage through said nozzle, butterfly valves in said two passages to regulate the flow of air therein, a fuel source, feed lines leading from said source to said two air passages, needle valves for regulating the flow of said fuel, a fuel passage and a fuel pocket in said piston into which fuel is forced from said air passages when the piston reaches a predetermined position of its stroke, means for igniting said fuel and means for forcing out the exhaust gases from said combustion chamber.

5. In combination, a cylinder having a combustion chamber, a piston adapted for reciprocation therein, two air passages having one of their ends leading into the cylinder and the other ends terminating into a single curved passage, a converging nozzle secured on the end of said passage, means for supplying air into said passage through said nozzle, a fuel source, regulated feed lines from said source to said air passages, means in said piston for receiving fuel from said air passages when the said piston reaches a predetermined position of its stroke, means for igniting said fuel, an ex-

haust port and a converging nozzle having an upward curved opening into the cylinder so that the cylinder may be completely evacuated of exhaust gases that are forced 5 out by air from the nozzle.

6. In combination, a crank case having a crankshaft positioned for rotation therein, two cylinders having combustion chambers extending horizontally from said case, pistons adapted for reciprocation in said cylinders, rods attaching said pistons to said crankshaft so that the reciprocation of the piston will simultaneously rotate said crankshaft, a propeller fitted on one end of 10 said crankshaft, and means for reciprocating said pistons, consisting of air passages leading into the cylinders, converging nozzles secured to the end of said passages and placed on said cylinder in the slipstream of 15 said propeller, a fuel source, feed lines from said source to said passages, means in said pistons for receiving fuel from said air passages when the pistons reach a predetermined position of their stroke, means for 20 igniting said fuel, exhaust ports and converging nozzles disposed in the slipstream of said propeller, having a curved opening into the cylinders so that the cylinders may be completely evacuated of exhaust gases that 25 are forced out through the said ports by air from the nozzles.

7. A device as set forth in claim 6 wherein in the converging nozzles, therein mentioned, are placed on the cylinders at an angle of between plus or minus thirty degrees from the axis of said propeller, so that the rotary velocity of the slipstream caused by the propeller can be efficiently used.

8. In combination a cylinder having a 30 combustion chamber, a piston adapted for re-

ciprocation therein, a fuel source, a spark plug placed in said cylinder adjacent the head thereof for igniting the fuel in said combustion chamber, a fuel pocket having an opening adapted to pass said spark plug 45 near the end of the outward stroke of said piston, a fuel passage in said piston, means for forcing fuel from said source into said pocket and also through said passage into said combustion chamber when the piston reaches a pre-determined position of its 50 stroke and a converging nozzle positioned on said cylinder and having an opening into said combustion chamber for forcing out the exhaust gases from said chamber after 55 the fuel has been ignited by said spark plug.

9. A construction as set forth in claim 8 wherein the passage in said piston is curved laterally so that the same substantially reverses itself in direction and the opening thereof into the combustion chamber is in the top of the piston head.

10. In combination, a cylinder having a combustion chamber, a piston adapted for reciprocation in the cylinder, a fuel source, a converging nozzle on the cylinder adapted to receive fuel from said source and pass it to the combustion chamber, means for igniting said fuel and a converging nozzle 65 through which air may be drawn to force 70 exhaust gases from the chamber.

11. A construction as set forth in claim 10, wherein one end of the piston is secured to a crankshaft, a propeller is mounted on the crankshaft, and the nozzles are positioned at an angle of plus or minus thirty degrees from the axis of the propeller and 75 in the slipstream thereof.

EDWARD A. STALKER.
